GRID FOR COOK-OUT GRILL

Richard Kates, Park Lane, Madison, N.J.

Filed Aug. 18, 1958, Ser. No. 52,238

Term of patent 14 years

(Cl. D81—25)

I claim:

The ornamental design for a grid for cook-out grill, as shown.
